UNITED STATES PATENT OFFICE.

RICHARD GABRIELSKY, OF JERSEY CITY, NEW JERSEY.

STRINGED MUSICAL INSTRUMENT.

SPECIFICATION forming part of Letters Patent No. 690,263, dated December 31, 1901.

Application filed April 4, 1901. Serial No. 54,309. (No model.)

To all whom it may concern:

Be it known that I, RICHARD GABRIELSKY, a citizen of the United States, residing at Jersey City, in the county of Hudson and State 5 of New Jersey, have invented certain new and useful Improvements in Mechanical Stringed Musical Instruments; and I do hereby declare the following to be a full, clear, and exact description of the invention, such as will 10 enable others skilled in the art to which it appertains to make and use the same.

This invention relates to mechanical or self-playing stringed musical instruments—such as zithers, autoharps, and the like—in which 15 the strings are mechanically struck and sounded by hammers and suitable operating mechanism connecting with star-wheels.

The object of my invention is to provide an improved self-playing or mechanically- 20 actuated stringed musical instrument which is simple in construction and arrangement, not liable to get out of order, and which shall be effective for producing clear harmonious tones.

25 One of the special objects is to provide for striking and sounding the strings by hammers, also for damping the strings by means of soft flexible devices applied to the hammers.

30 Another object is to provide for giving a piano tone or effect by means of a rod and long eccentric adapted to bear upon the faces or edges of the elbow-levers with which the hammers are connected.

35 The parts and combinations of parts constituting my invention will be set forth in the claims.

The details of construction of my improved devices are illustrated in the accompanying 40 drawings, in which—

Figure 1 represents a top plan view of a stringed musical instrument and my mechanical devices for playing the same. Fig. 2 represents a vertical transverse section of the 45 same on line 2 2, Fig. 1. Fig. 3 represents a rear side elevation showing the star-wheels and part of the sounding-board. Fig. 4 represents a detail view, on enlarged scale, showing a hammer, star-wheel, and connecting 50 mechanism. Fig. 5 represents a rear elevation, on enlarged scale, showing part of the star-wheels and the retarding or pressure springs therefor.

I have shown the improved devices constituting my invention applied to a zither; but 55 they may be applied to other stringed musical instruments.

The strings 2 are stretched over the sounding-board 1 and attached to the tuning-pins in the usual manner. The frame 3, carrying 60 the star-wheels, tune sheet or disk, and operating mechanism, is clamped to the sounding-board 1, as shown in Figs. 2 and 3, and a separate frame 4, which may be called the “hammer-frame,” is secured at one end to 65 said frame 3 and at or near the other end is supported by a post 4^a, fixed in the sounding-board, as shown in Fig. 1. The supporting-post 4^a may be placed at any convenient part of the frame. For the purpose of illustration 70 I have shown only part of the strings and hammers therefor in Figs. 1 and 2, though it will be understood that in practice the strings are stretched over the whole width of the sounding-board. The star-wheels 5, of which 75 there is one for each hammer, are placed loosely on a shaft 6, which is supported in the posts 7. These posts 7 are arranged one between each pair of the adjacent star-wheels and serve for spacing them apart. They are 80 provided at the rear with transverse slots 8 for inserting the rod or shaft 6, which carries the star-wheels, as shown in Figs. 3 and 4. At certain intervals on the shaft 6 are placed the rollers 9, which are of slightly greater diameter 85 than the star-wheels for supporting the tune sheet or disk 13. Other rollers 10, supported on a swinging shaft, bear upon the upper surface of the tune-sheet 13. Any suitable gearing 11 is employed for turning the tune-sheet 13, and a handle 12 may be applied for 90 turning the gearing by hand. Any suitable mechanical power may be substituted for the handle or crank 12. The tune sheet or disk 13 is supported centrally upon the post 14, so 95 that its teeth or note projections will engage with the points of the star-wheels, as indicated in Figs. 3 and 4. Certain pressure-springs 15 are set in an inclined position in a metal strip 15^a, as shown in Fig. 5, and arranged 100 to bear upon the faces of the star-wheels for retarding or holding them steady, so as to

hold each of them in place after it has been moved by a tooth of the tune-sheet. An inclined spring-presser 15 is arranged to bear upon each star-wheel.

5 Just in front of the posts 7 are secured a series of posts 16, to the upper ends of which are pivotally connected the elbow-levers 17 by means of a rod 18, passing through the posts and levers, as shown in Fig. 4. The 10 elbow-levers are properly spaced apart on the rod 18 and are so arranged that the outer end of each lever will be engaged by the teeth of a corresponding star-wheel, as shown in Figs. 1 and 4. The upper ends of levers 17 15 are perforated for attaching the connecting-wires 26, which are also attached to the hammers 19. The series of hammers 19 are pivotally connected to the short posts 20, arranged all along the front inclined bar 4^b of 20 the frame 4, as shown in Figs. 1 and 4. The hammers are made with comparatively wide lower ends, which strike the strings, and are provided above their pivots with upwardly-projecting lugs 21, which are perforated for 25 attaching the connecting-wires 26. They are also each provided with a rear extension-lug 22, to which is applied a spiral spring 23, which bears at its lower end upon the bar 4^b of the frame, as clearly shown in Fig. 4. The 30 horizontal part of the hammer 19 is preferably made thin and flexible or springy, so that it will readily rebound after striking the string. The wide lower end of each hammer or any desired number thereof is provided 35 with a hole 19^a and a notch 19^b for attaching the soft flexible damper 25. This damping device may be a string of fibrous material or other soft and flexible material. This damping device passes around under the string 2 40 and damps such string in a satisfactory manner.

In order to produce a piano tone or effect, I provide a rod 27, having an eccentric 28 along its length, the rod being supported in 45 bearings in brackets 29, which may be secured to the posts 16. The eccentric 28 is so placed that it may be turned to bear lightly or more strongly upon the front edges of the elbow-levers 17. The eccentric rod 27 will be turned 50 and adjusted by the head or disk 31, as shown in Fig. 1. The eccentric 28 being turned to bear upon the front edges of the elbow-levers 17 will slightly arrest the forward movement of said levers when released from the 55 star-wheels and will therefore prevent the connected hammers 19 from striking the strings 2 with as much force as they otherwise would. A softer tone is therefore produced.

60 It will be understood that a star-wheel when engaged by a tooth of the tune sheet or disk will be partly rotated, thereby pressing down the adjacent end of an elbow-lever and raising a hammer. Now when the elbow-lever 65 is released the spring 23 will act to throw the hammer down onto the string to sound the same. This action of the spring is important

when the zither is played in a vertical position. By use of the springs 23 the zither can be played either in a horizontal or vertical 70 position.

Having fully described my invention, I claim as new and desire to secure by Letters Patent—

1. In a mechanical musical instrument, the 75 combination with the strings, stretched over the sounding-board, and pivoted hammers for striking the same, of a series of star-wheels, intermediate connections and actuating devices adapted to be engaged by the star-wheels, 80 for actuating the hammers, substantially as described.

2. In a mechanical musical instrument, the combination with strings stretched over the sounding-board, and a series of star-wheels, 85 of pivoted hammers, pivoted elbow-levers adapted to be engaged by the star-wheels, and connections from said levers to the hammers, substantially as described.

3. In a mechanical musical instrument, the 90 combination with the strings and a series of star-wheels, of a series of pivoted hammers, a spring for each hammer, a series of elbow-levers adjacent to the star-wheels, and connections therefrom to the hammers, substantially as described.

4. In a mechanical musical instrument, the combination with the hammers, elbow-levers and connections, of a rod having an eccentric adapted to be turned to bear more or less upon 100 said elbow-levers for giving a piano tone or effect, substantially as described.

5. In a mechanical musical instrument, the combination with a string and a hammer therefor, of a damping device applied to the 105 striking end of the hammer, substantially as described.

6. In a mechanical musical instrument, the combination with a string and hammer therefor, of a flexible damping device attached to 110 the striking end of the hammer and passing around the string, substantially as described.

7. In a mechanical musical instrument, a horizontal string, a pivoted hammer above the string having a comparatively wide striking end, a lug projecting above the pivot for attaching a connecting-wire, a rearwardly-projecting lug and a spring bearing thereon to throw the hammer down upon the string, substantially as described.

8. In a mechanical musical instrument, a horizontal string, a pivoted hammer above the string and having a lug projecting above its pivot, a connecting-wire attached to said lug, an actuating device to which said wire is also 125 connected, and a spring connecting with each hammer to throw it down upon the string, substantially as described.

In testimony whereof I affix my signature in presence of two witnesses.

RICHARD GABRIELSKY.
